Augustus B. Sargentton.

ATTORNEY.

Patented Apr. 13, 1926.

UNITED STATES PATENT OFFICE.

WILLIAM S. FEENY, OF PHILADELPHIA, PENNSYLVANIA.

HOLDER FOR AWNING AND LIKE HEAD RODS.

Application filed October 14, 1925. Serial No. 62,365.

To all whom it may concern:

Be it known that I, WILLIAM S. FEENY, a citizen of the United States, residing at Philadelphia, in the county of Philadelphia and State of Pennsylvania, have invented a new and useful Holder for Awning and like Head Rods, of which the following is a specification.

The principal objects of the present invention are, first, to provide a holder of the type mentioned useful on both horizontal or ceiling surfaces or on vertical or building face surfaces; second, to provide a holder of the type mentioned which will permit the awning head rod to be placed directly beneath and close up to the under surface of a projection, such as a molding, thus leaving no space between the top of the awning and the under side of the projection; third, to provide a device of the character mentioned which will accommodate head rods of different diameters; fourth, to provide for ready detachment of the pulleys whilst guarding against their accidental detachment; fifth, to provide for the ready and convenient attachment and detachment or, as it is sometimes called, putting up and taking down of the awning; and sixth, to provide for hiding the holder under the awning and thus presenting a neat appearance.

Other objects of the invention will appear from the following description, and the invention may be said to comprise a holder for awning and like head rods including two plate elements arranged in sliding relation and each provided at one end with one pair of spaced confronting clamping jaws, one of said plates being provided with screw or bolt holes arranged near the root of its clamping jaw and a slot-and-screw clamping adjustment connecting said plates, with or without pulley hooks on the last mentioned plate and guards on the other plate for cooperation with the hooks.

The invention also comprises the improvements to be presently described and finally claimed.

In the following description reference will be made to the accompanying drawing forming part hereof and in which

Figure 1 is a front view of a holder embodying features of the invention and showing pulleys.

Fig. 2 is a side view of the same showing or indicating a head rod and part of an awning, and

Fig. 3 is a front view illustrative of different positions of the parts.

In the drawing 1 and 2 are plate elements arranged in sliding relation and each is provided at one end portion with one of a pair of spaced confronting jaws 3 and 4. The plate 1 is provided with screw or bolt holes 5 arranged near the root of its clamping jaw 4. As shown these holes 5 for fastenings are provided through lateral ears 6 extending from the plate element 1. The slot 7 shown as provided in the plate element 2 and the set screw 8 shown as extending through the slot 7 and engaging the plate element 1 constitute a clamping adjustment connecting the plate elements 1 and 2. 9 are pulley hooks arranged at the end portion of the plate element 1 and projecting toward the jaw 4. They are adapted to receive the eyes 10 of pulleys. 11 are guards projecting laterally from the plate element 2 and adapted to cooperate with the hooks 9.

In use the holder is mounted in plate by bolts, screws or other attaching means inserted through the openings 5 and since the clamping jaw 4 projects beyond the plate element 1 the jaw 4 can be brought close up to any surface, for example, the under surface of a molding or in line with any vertical surface such as the face of a building. This is an important matter of improvement in the appearance of the awning as a whole. Furthermore the lower jaw 3 and the set screw 8 are inside of the awning which also improves the appearance of the awning. To put up the awning the pulley eyes may be applied to the hooks 9 when present by loosening the set screw and tipping the plate element 2, as shown in Fig. 3, thus causing the guard 11 to clear the left-hand hook in that figure. Reversely a pulley can be applied to the righthand hook. The hem and head rod of the awning are placed between the jaws 3 and 4 and the plate element 2 is pushed or slid into position for causing engagement of the jaws with the rod and hem. Then the set screw 8 is tightened. When thus assembled neither the pulley nor the awning structures can become accidentally detached from the holder. To take the awning down the set screw is released and the clamping plate 2 may assume the position shown in dotted lines in Fig. 3, so that the pulleys will not become detached until required. To detach the pulleys the plate element 2 is turned as above

described. The sliding adjustment of the jaws permits them to cooperate with rods of different diameters, of course within reasonable limits. The holder may be constructed 5 of iron, steel, brass or other metals. However, good results can be obtained by constructing it of iron with the exception of the set screw which can be of brass and when that is the case the possibility of the set 10 screw rusting against turning movement is avoided. It is an advantage of the described construction that the location of the fastening devices which pass through the holes 5 is such that the pull of the awning is in the direction of their length so that tendency to 15 enlarge the openings in the wood into which the fastening devices are inserted is obviated.

It will be obvious to those skilled in the art

that the invention is not limited to details of 20 construction and arrangement or as to mere matters of form or as to the conjoint use of all its features or otherwise than as the prior art and the appended claim require.

I claim:

A holder for awning and like head rods including two plate elements arranged in sliding relation and each provided at one end portion with one of a pair of spaced confronting clamping jaws, one of said plates being provided with holes arranged near the root of its clamping jaw, a slot-and-set screw clamping adjustment connecting said plate elements, pulley hooks on the last mentioned plate element, and guards on the other 30 plate element for cooperation with the hooks. 35

WILLIAM S. FEENY.
